TACK PULLING MACHINE

Roger L. Griffin, Marblehead, and Norman V. Moore, Danvers, Mass., assignors to A. C. Lawrence Leather Company, Peabody, Mass., a corporation of Maine

Application July 1, 1938, Serial No. 217,084

29 Claims. (Cl. 254—18)

The present invention relates to tack pulling machines, and more particularly to a machine designed primarily for removing tacks from boards upon which hides or skins have been stretched and dried.

5 In practice, the tanned skins while still wet are stretched out and tacked to the wooden stretching frames or "boards" as they are called, which are then passed through drying chambers after which the tacks are withdrawn and the 10 dry skins removed from the boards.

It is the object of the present invention to provide a novel and improved tack pulling machine for automatically removing the tacks from a plurality of boards presented successively to the machine by a conveyor system.

15 Another object of the invention is to provide a tack pulling machine having light weight and resilient tack engaging members, which not only will yield in the event of misengagement of said 20 members with the heads of the tacks and thus avoid bending the tacks or driving them further into the board, but which, because of such resiliency of the members, will also propel or throw the tack clear of the board and leather and into 25 a collector.

25 A further object is to provide a tack pulling machine having improved hold-down mechanism for preventing the skin from being lifted into contact with the tack pulling elements as the 30 tacks are withdrawn, or any portion of the skin which may have been detached from the board during the drying operation from becoming entangled with the tack-pulling device, thus preventing injury to the leather and damage to 35 the tack-pulling device.

Another object is to provide a simple and inexpensive construction of tack-pulling tool having 40 tack engaging elements in the form of tensioned wires wherein the tension on the wires may be easily adjusted or varied as desired while automatically maintaining an equal tension on each. Also, wherein the wires may be removed and replaced with a minimum expenditure of effort and time.

45 Still another object of the invention is to provide improved means for collecting and delivering tacks from the machine as they are pulled from the boards and skins.

50 To the above ends the present invention contemplates a continuously rotating tack pulling tool having resilient tack engaging members adapted to operate across the width of a board. Also, a traveling hold-down mechanism which moves with the board and skins and holds the 55

skin down firmly on the boards as they pass beneath the tack-pulling tool. Also, a conveyor or other means for feeding the boards beneath the tack-pulling tool and a hood or other suitable collecting device for catching the tacks as they are thrown off by the resilient tack-pulling members, together with delivery means for discharging the collected tacks at some convenient point outside the machine.

5 In the drawings illustrating the preferred embodiment of the invention, Fig. 1 is a view in front elevation, partly in section, of the complete machine, a portion of the enclosing casing and of the hold-down mechanism being omitted for purpose of clearness of illustration; Fig. 2 is a sectional view in side elevation taken along the line 2—2 of Fig. 1; Fig. 3 is a longitudinal sectional view, on a larger scale, of a portion of the tack-pulling tool and hold-down mechanism, and showing a board and skin positioned beneath said tool; Fig. 4 is a transverse sectional view of the parts illustrated in Fig. 3 taken along the line 4—4 of said figure; and Fig. 5 is an end view of the tack-pulling tool with the tack-pulling members or wires omitted, the view being taken along the line 5—5 of Fig. 3.

Briefly, the machine illustrated in the drawings comprises a conveyor for feeding the boards with the dried leather tacked thereto past a rotary tack-pulling tool which is provided with a cylindrically arranged series of longitudinally extending, tightly stretched wires to engage the under side of the heads of the tacks and first withdraw them and then throw them forcibly into an adjacent collector or hood. A continuously moving transverse belt or conveyor beneath the hood receives the tacks therefrom and carries them outside the machine where they fall into a receptacle.

The hold-down mechanism comprises a series 40 of spaced transverse rods or bars carried at their ends on endless chains, continuously driven in the same direction and at the same speed as the boards themselves, and arranged to be brought down between the tacks to engage and hold the skin from rising as it passes beneath the tack-pulling tool.

The feeding mechanism which carries the boards 7 and attached hides 9 beneath and past the tack-pulling tool comprises carriages 11 supported by the flanged wheels 13 on opposite ends of the shafts 14 mounted on and extending across the carriage. The wheels 13 run upon rails 15 secured upon the transverse members 17 of the machine frame. Upon each carriage 11 is posi- 50 55 60 65

tioned the supplementary platform 19 having upwardly extending driving brackets or arms 21. These arms engage in notches 23 in the depending flanges 25 of the channel members 27 which receive the marginal portions of the strips or pieces of wood making up the boards 7, and securely bind the whole together. In order to provide for the use of the boards either side up, the channel members are formed with correspondingly upstanding flanges 31 having driving notches 33.

The conveyor carriages are moved along the tracks by endless chains 35, one on each side of the machine, attached to each carriage by bearing pieces 36 which fit over the ends of the carriage shafts 14. The chains run within channel member 37 mounted on the opposite ends of the transverse frame member 17, and are driven in conventional fashion by a source of power, not shown. In order to provide support for the conveyor chain 35 between the flanged wheels 13 the rails 38 are provided (see Fig. 1), mounted on transverse members 17 of the machine frame.

Preferably, in order that the boards may be positioned accurately beneath the tack-pulling mechanism and not be affected by variations in the carriages, supplementary guiding rolls may be provided adjacent the tack-pulling tool for the platform. Thus idler rolls 39 mounted on the sides of the machine frame serve to align the platform with respect to vertical position, these rolls bearing on the under side of the platform, while horizontal alignment is insured by idler rolls 41, 43, which bear against the flanged end members of the boards themselves. The pivots of idler rolls 41 on the left hand side of the machine, as viewed in Fig. 1, are spring-pressed inwardly so that the board will always bear against rolls 43 mounted in fixed position 40 on the opposite side of the machine, thus eliminating any possibility of the board canting and becoming jammed cornerwise. Stop screws 45 limit the amount the idler rolls 41 may move inwardly when no board is in engagement therewith.

The tacks are pulled from the boards by means of a rotating tool or reel (see Figs. 3, 4 and 5), which rotates in a counterclockwise direction, as viewed in Fig. 2, so that the bottom or operative portion of the tool moves oppositely to the boards as they pass through the machine on the conveyor. The tack-engaging elements of the reel consist of wires or thin rods 47 arranged parallel about the reel shaft 49 as elements of a cylinder. A satisfactory arrangement consists of three of these wires spaced at 120° apart in the reel. The wires are stretched under tension between the reel ends or heads 50 and 51 mounted on the shaft and provided with the circular openings 52 having short radial slots 53 directed outwardly toward the periphery into which slots the wires slide in assembling the reel. The ends of the wires have secured thereto small conically-shaped buttons or beads 54, the wire beyond the beads being headed over to retain the beads. In assembling, these beads are passed through the openings 52 in the heads and then seated in an annular V-shaped groove 55 in the outside face of the reel heads, the bottom of the groove being of the same radius as the closed ends of the slots 53.

Reel head 50 is of integral construction with its hub fixed to the shaft 49 by a set screw or other suitable means, while the head 51 is so constructed as to be capable of axial movement to

adjust the tension of the wires and to permit replacement of the same. Provision is also made for slight angular movement of the head, or a portion thereof, to equalize the tension of the several tack-pulling wires. The construction of the adjustable end 51 is illustrated in Figs. 3 and 5 and comprises a sleeve 56 secured to the reel shaft by the set screw 57. One end of the sleeve is externally threaded as at 59, and a key way 61 is also provided. The end plate or disc 63 which supports the wires is loosely mounted on the sleeve 56 so as to permit free axial and substantial angular movement thereon, a key 65 secured to said end plate by screw 67 and fitting loosely in the key way 61 preventing relative rotation of the parts. The end plate 63 is moved outwardly along the sleeve by means of an internally threaded collar 69 which engages the threaded portion 59 of the sleeve. The collar is provided with recesses 71 about its circumference to receive a suitable tool or wrench for rotating the same.

As shown in Fig. 3, the mutually engaging faces on the disc 63 and threaded collar 69 are spherically concave and convex, respectively, as indicated at 73, so that the disc is free to tip to a limited degree with respect to the sleeve about this universal joint or bearing. This permits the disc or head 63 to adjust itself so that the tension on each of the three tack pulling wires 47 will be substantially the same irrespective of slight variations in the lengths of wires between their upset ends.

The wires 47 during the tack-pulling operation are deflected from their normal position by the resistance of the tack to withdrawal, so that when the tack does pull out, the wire snaps back and vibrates with substantial amplitude. Such vibration tends to weaken the wires adjacent the supporting ends or heads, so that breakage may result. To dampen this oscillation or vibration, supplementary discs 73, illustrated in Figs. 3 and 4, are mounted on the reel shaft intermediate and adjacent the reel heads 50 and 51. The supplementary discs are secured to the reel shaft 49 by means of set screws 75 and have radial slots 77 extending axially through the outer portion of the discs. The radial inner end of each slot is enlarged at 79 to permit the passage therethrough of the heads 54 on the ends 50 of the wires, in assembling the reel. Preferably the radius of the outer end of the slots 77 is slightly greater than the radius of the outer end of the slots 53 in the ends or heads 50 and 51, so that the wires will necessarily extend in a straight line from one end of the reel to the other.

As the tacks are withdrawn from the board by the operation of the tack-pulling reel, there is a tendency of the hide to stick to the tacks and be lifted from the board and drawn into contact with the rapidly moving wires with consequent injury. In order to keep the hides flat on the boards during their passage through the machine, hold-down mechanism is provided analogous to an inverted conveyor system, having thin crossbars which rest on the hide between the tacks and move along with the boards at the same rate of speed.

This hold-down mechanism comprises endless side chains 81 (see Fig. 2), running over large sprocket wheels 83 secured to transverse shafts 85 and 87. These shafts are journaled in bearings 88 secured to the sliding plates 89 normally fixedly mounted on the sides of the machine 75

frame, but arranged for up and down adjustment, the frame being provided with vertical slots through which extend the ends of the shaft and the adjusting bolts 91 for vertically adjusting the parts.

Extending across the machine from one chain to the other are a plurality of transverse bars or rods 93 slightly shorter than the width of the boards, but longer than the tack-pulling reel. The rods 93 have reduced end portions 94 which are secured to the chains at regular intervals by means of a two-part connection, as shown in Fig. 3. This comprises an outer sleeve 95 having an opening in the end of less diameter than the bore of the sleeve. In assembling, the reduced end 94 of the rod 93 is passed through this opening and then upset or headed over, thus securing the outer sleeve to the end of the rod, but with capacity for limited relative longitudinal movement. Pinned within the sleeve at its open end is the inner member 96 having an extension 97 of reduced diameter which serves as the pivot pin of the chain. Conveniently, the parts 96 are assembled first with the chain 81, thus permitting the positioning of the chains on the sprockets and the later attachment of the rods 93.

The rods are sufficiently flexible so that they will adapt themselves to the varying arrangement of the tacks, slipping down between adjacent heads and thus permitting the engagement of all tacks by the wires of the reel.

In order to avoid the possibility of tacks or the leather being jammed as they pass beneath the shafts 85 and 87, these are adjusted vertically so that normally there would be about one and a half inches clearance between the rods directly under the shafts and the boards on which the leather is tacked, sufficient slackness being provided in the chains 81, however, to permit the rods to rest upon the leather throughout substantially the entire length of the lower horizontal leg of the chains. The slackness thus provided, supplemented by the cumulative looseness of the chain pivots, permits forward and backward bodily movement of the rods which further assists in the accommodation of the hold-down rods to the work. The chain during its idle or return movement is supported by the idler or sprockets 98 which prevent sagging in a long heavy loop and the consequent take-up of slack along the board contacting portion.

The hold-down chains 81 are driven by the sprocket 83 on the shaft 87, which in turn is driven from the return leg 99 of one of the conveyor chains by means of the sprocket 100 on horizontal shaft 101, bevel gears 102, vertical shaft 103 and gears 104, the ratios being such that the linear speed of the hold-down rods is exactly the same as that of the boards carrying the leather, so that the rods after they are brought into contact with the leather have no movement relatively thereto until they move out of contact after the tack-pulling operation is completed. Preferably, the shaft 103 is formed in two sections connected by means of a sleeve and shear pin to protect the mechanism from injury in the event that the hold-down bars or other actuating mechanism become jammed for any reason. To prevent the rods 93 from being raised by curved edges of the leather or otherwise, so that they contact the rapidly rotating peripheries of the heads 50 and 51 of the tack-pulling tool and are damaged thereby, two rolls or discs 105 have been provided, one at each end of the rotating tool, freely ro-

tatable on ball bearings 106 on the shaft 49 immediately above and slightly spaced from the sprocket chain 81. These discs are of slightly larger diameter than the heads of the tack-pulling reel, but will prevent upward movement sufficient to bring the rods into damaging contact with the heads of the reel.

The sprockets and chains of the hold-down mechanism are enclosed between the sides 107 and top 108, the end portions 109 of the latter being hinged at 110 to permit their being raised to give access to the sprocket wheels, chains, and bars at each end of the machine. These end portions terminate well above the path of movement of the boards through the machine to provide an ample sized opening for the passage of boards therethrough.

As the tacks are pulled from the boards they are thrown from the reel more or less upwardly and forwardly with considerable force. In the illustrative embodiment of the invention collecting means have been provided not only to prevent the escape of the flying tacks into the room or striking an operator or lodging in the operative parts of the machine, but also for gathering and removing them from the machine at a predetermined point in a continuous operation.

The collector or hood 111, best shown in Fig. 2, extends entirely across the machine between the sides 107 and serves as a barrier or stop for the tacks. A curtain or rebound trap 112, comprising a plurality of strings or wires hanging from the peak of the hood, prevents the tacks from bouncing out of the hood after striking the same, stopping the tacks either as they are thrown off from the tack-pulling reel or on the rebound from the back of the hood after they have penetrated the curtain. In order to avoid the possibility of fire from sparks caused by the impact of the tacks on the hood or other parts, the curtain, when formed of string or other combustible material, will be chemically treated to render it fireproof.

The bottom of the hood is formed with a wide shallow channel 113 in which runs an endless conveyor belt 114, upon which the tacks fall after they are thrown against or through the curtain. This belt runs through openings in the sides of the machine and over upper pulleys 115 and 116 at each end of the channel beneath the conveyor track, and over lower pulleys 117 rotatably mounted between vertical members 119 comprising part of the frame of the machine. The pivot shaft of upper pulley 116 is arranged for adjustment by means of threaded studs 121 to obtain correct tension of the belt, while pulley 115 is mounted in fixed pivots and is rotated at a slow rate to drive the conveyor belt by mechanism hereinafter described.

The tacks are discharged from the belt as it passes over the pulley, falling into a suitable container.

The tack pulling reel is rotated at moderately high speed, of the order of several hundred revolutions per minute, by means of a motor 123 which drives the reel through a conventional V-belt 125 running over motor pulley 127 and pulley 129 on the reel shaft. At the other end of the reel shaft is a small pulley 131, which drives pulley 133 of a speed reducing mechanism 135 by belt 137. The driving pulley for the tack conveying belt is driven from the low speed shaft of the speed reducer by a chain 139 running over sprockets 141 and 143. The reduction in speed between the reel shaft and the belt driving pulley 75

should be such as to provide a conveyor belt speed of the order of a few feet per minute.

In operation the feed or conveyor mechanism for the boards is driven continuously and at a slow rate. The boards with the dried skins tacked thereto are presented to the conveyor at some distant point by hand or machine in any suitable manner, and are positioned on the platform of the carriages with the driving brackets or projections of the platform entering the driving recesses in the boards.

As the carriages carrying the boards approach the tack pulling tool, the carriages ride up on the supporting rollers to bring the boards at 15 proper height for the tack pulling operation, and at the same time the side guide rolls hold the boards from angular displacement.

Meanwhile the boards with their tacked skins have come beneath the first sprocket and the hold down bars have been brought downwardly into contact with the board and skin, passing between the tacks and shifting bodily or flexing to one side or the other of the tacks which they strike in their descent. The boards reach the 20 rotating tack pulling reel with the skins held firmly between the boards and the hold down bars, with the tacks standing substantially upright with their heads well above the bars. The tack pulling wires which are moving rearwardly just above the hold down bars engage beneath the 25 heads of the advancing tacks and pull them out, throwing them into the hood where they fall onto the belt conveyor by which they are carried to a point outside of the machine and discharged 30 into a receptacle.

After the tacks are withdrawn the board and skin continue to be fed along with the skin tightly clamped against the board by the hold down bars. Not until the skin is well past the tack pulling 35 reel and out of any possible contact therewith are the bars raised and the skin freed.

Due to the resilient character of the tack pulling members, i. e., the wires, there is more or less yielding engagement of the latter with the 40 tacks, thus greatly reducing, if not eliminating entirely the possibility of a bending over of the tacks without pulling them, as may and does occur where a rigid, unyielding tack engaging tool is employed.

Furthermore, the resiliency of the tool throws the withdrawn tacks with such force and accuracy that they may be collected at some convenient 45 point a substantial distance from the tool.

While the invention has been illustrated and 50 described as embodied in connection with a machine for pulling tacks from boards and skins carried thereby, it is not necessarily limited to such a use, but may be employed in other machines and for other uses within the scope of the appended claims. Nor is the invention limited to the specific forms and constructions herein shown and described, but these may be varied and altered as desired within the language of the 55 claims.

The nature and scope of the invention having 60 been thus described, what is claimed is:

1. A tack pulling machine having, in combination, a rotating tack pulling tool, means for supporting the work as it is fed past the tool, and a 65 hold-down mechanism traveling with the work to hold the latter when the tacks are withdrawn by the tool.

2. A tack pulling machine having, in combination, a rotating tack pulling tool, means for feeding the work beneath and past the tack pulling 70

tool in a direction opposite to the movement of the tack engaging portion of the tool, and devices engaging the work in advance of the tool and movable with the work past the tool to hold the work against the action of the tool. 75

3. A tack pulling machine having, in combination, a rotating tack pulling tool, feeding mechanism for feeding the work past the tool comprising conveyor chains, carriages connected to the chains, supplementary platforms on the carriages for supporting the work, and means independent of the carriage for supporting the platforms while guiding the same past the tack pulling tool. 10

4. A tack pulling machine having, in combination, a rotating tack pulling tool, feeding mechanism for feeding the work-supporting boards past the tool and comprising conveyor chains, carriages connected to the chains, and supplementary platforms on the carriages for supporting the boards, and guiding mechanism for guiding the work past the tool comprising rolls for engaging the platform to position the same vertically with respect to the tack pulling tool, and edge guide rolls for engaging the edges of the 15 board to position the same horizontally with respect to the tack pulling tool. 20

5. A tack pulling machine having, in combination, a rotating tack pulling tool, work-supporting boards to which the work is tacked, provided with metallic edge members having notched flanges, feeding mechanism for feeding the boards past the tack pulling tool comprising conveyor chains and fingers connected therewith for engaging the notches in said flanges, and means 25 for engaging said members for positioning the boards laterally with respect to the tack pulling tool. 30

6. A tack pulling machine having, in combination, a tack pulling tool, means for feeding the work past the tack pulling tool, and hold-down 35 means comprising a plurality of bars extending transversely of the direction of feed of the work, and devices for moving the bars with the work while in engagement therewith during the tack pulling operation. 40

7. A tack pulling machine having, in combination, a tack pulling tool, means for feeding the work past the tack pulling tool, and hold-down devices for engaging and traveling with the work during the tack pulling operation, said devices 45 comprising a pair of spaced chains and a plurality of flexible, work-engaging bars arranged transversely of the direction of feed and carried by the chains. 50

8. A tack pulling machine having, in combination, a tack pulling tool, means for feeding the work past the tack pulling tool, and hold-down devices for engaging and moving with the work during the tack pulling operation, said devices comprising a pair of spaced endless conveyor 60 chains with oppositely moving sections and work-engaging members carried thereby and extending transversely of the direction of feed, and means for supporting the chains with the oppositely moving sections of each chain spaced apart and 65 the tack pulling tool positioned between said sections. 70

9. A tack pulling machine comprising a rotary tack pulling tool having resilient members, a collector adjacent the tool to receive withdrawn tacks, and depending means within the collector to prevent the escape of the tacks therefrom. 75

10. A rotary tack pulling tool having a plurality of independent, resilient tack engaging mem- 75

bers provided with uninterrupted tack engaging faces extending substantially the axial length of the tool.

11. A rotary tack pulling tool having resilient tack engaging members comprising a plurality of long, thin tack engaging members, arranged parallel to the axis of the tool and supported adjacent their ends with free intermediate tack engaging portions.

10 12. A rotary tack pulling tool comprising a shaft, a pair of supporting heads spaced on said shaft, and a plurality of tack pulling wires stretched between the supporting heads parallel to the axis of the tool.

15 13. A tack pulling tool comprising a shaft, a pair of supporting heads spaced on the shaft, a plurality of tack pulling wires supported by the heads parallel to the axis of the shaft, one of the heads being movable axially on the shaft to 20 adjust the tension of the wires.

25 14. A tack pulling tool comprising a shaft, supporting heads spaced on the shaft, tack pulling wires stretched between the heads parallel to the axis of rotation, and means contacting the wires intermediate the heads to eliminate vibration of 25 the wires.

30 15. A tack pulling machine having, in combination, a rotary tack-pulling tool, means for feeding the work with the tacks partially embedded therein past the rotating tool, and means movable with the work and engaging the same for holding down the work adjacent the tool.

35 16. A tack pulling tool comprising a pair of spaced heads, tensioned wires extending between the heads, one of the heads being supported on a universal mounting to permit tilting, thereby to equalize the tension on the several wires.

40 17. A rotary tack pulling tool having a plurality of tensioned, resilient tack pulling members.

18. A rotary tack pulling tool having three tack engaging tensioned wires.

45 19. A tack pulling tool comprising a shaft, supporting heads on the shaft, tack pulling wires stretched between the heads, and members rotatably mounted on the shaft outside the heads and of greater diameter than the same.

50 20. A tack pulling machine having, in combination, a rotary tack pulling tool, means for feeding past the tool boards to which skins or other material have been tacked, and independently rotatable means carried by the tool for spacing the boards therefrom.

55 21. A tack pulling machine having, in combination, a tack pulling tool, means for feeding the work past the tool, hold-down devices comprising a plurality of work-engaging members traveling with the work, and means for preventing contact of the work-engaging members with said tool.

60 22. A tack pulling machine having, in combination, a rotating tack pulling tool, means for feeding the work past the rotating tool, hold-down devices comprising a plurality of work-engaging members traveling with the work, and independently rotatable means carried by the tack pulling tool for preventing contact of the work-engaging members with said tool.

65 23. A tack pulling machine having, in combination, a rotary tack pulling tool, means including conveyor chains for feeding the work

past the tool, hold-down devices comprising a plurality of work-engaging members arranged transversely of the direction of feed, and means actuated by the conveyor chains to cause said work-engaging members to travel with the work past the tool at substantially the same rate of speed as the work.

5 24. A tack pulling machine having, in combination, a tack pulling tool, means for feeding the work past the tool, hold-down devices for engaging and moving with the work during the tack pulling operation, said devices comprising a pair of spaced endless chains with oppositely moving sections and work-engaging members carried thereby and extending transversely of 15 the direction of feed, means for supporting the chains with oppositely moving sections of each chain spaced apart and the tack pulling tool positioned between said sections, a collector positioned adjacent the tool between said sections, and a conveyor comprising an endless belt running between said sections transversely to the direction of the work feed for receiving and withdrawing tacks from the collector and discharging the tacks at one side of the machine. 25

25 25. A tack pulling machine comprising a rotary tack pulling tool having resilient members, a collector adjacent the tool to receive the withdrawn tacks, and a fireproof curtain within the collector to prevent the escape of the tacks 30 therefrom.

35 26. A tack pulling machine having, in combination, a rotating tack pulling tool and means for feeding past the tool boards to which the work is tacked with the headed portions of the tacks projecting from the boards, said tool comprising tack engaging members having a small radius of rotation to cause the members to engage the tacks with a substantial component of motion normal to the surface of the boards, thereby to 40 withdraw the tacks approximately in the line in which they were driven.

45 27. A tack pulling machine comprising a rotary tack pulling tool, having resilient tack pulling members and a collector adjacent the tool 45 at the side thereof in the direction from which the work approaches and into which collector the withdrawn tacks are thrown by the resilient members and collected.

50 28. A tack pulling machine comprising a rotary tack pulling tool having resilient members beneath which the work is passed, a collector positioned above the work adjacent the tool and on the side thereof in the direction from which the work approaches, and having an imperforate 55 bottom and a conveyor supported on the imperforate bottom of the collector to receive the tacks withdrawn from the work and thrown by the resilient members of the tack pulling tool and to discharge said tacks at a distant point. 60

55 29. A rotary tack pulling tool comprising an elongated flexible elastic tack pulling member and means for supporting said member to permit the same to engage the tacks in the work and to be extended thereby, and to withdraw and 65 discharge the tacks by contraction of the elastic member.
